**PRESSES FOR PRODUCING CONTINUOUS
WEBS OF MATERIAL**

Matthias Weiss, Vienna, Austria, assignor to Maschinenfabrik Andritz Actiengesellschaft, Graz-Andritz, Austria

Application January 22, 1954, Serial No. 405,625

8 Claims. (Cl. 100—154)

The present invention relates to a press for producing continuous webs of material between two endless conveyor bands or belts passing round a number of upper and lower rollers. A press of this kind is used mainly for removing the water from or for thickening and compressing masses of wet fibrous material. By fibrous material is to be understood, for example, paper pulp, mechanical wood pulp, cellulose, wood shavings and other materials of a vegetable, animal or mineral nature. Some of these substances oppose considerable resistance to the removal of the water, formation of a skin and compression, this being so for instance when the substance is swollen or is more or less loose or contains stringy admixtures or constituents, such as, for instance, peat, coconut husks or the like, or crumbly, crystalline or granular constituents, such as for example in the case of certain ground waste or by-products. The press can also be used however for pressing materials which are free from water consisting for example of filling substances and a synthetic resin binding medium.

One type of press has already been proposed in which the upper and lower rollers are arranged in groups each consisting of two or more pairs of oppositely lying rollers, the ends of the rollers of each group being mounted in bearing plates adjustable as regards height. In order to bring about a thorough removal of the water and compression of the material in question very large pressing pressures have to be used and this makes it necessary for the frame for the numerous rollers and particularly the common beam on which the bearing plates bear to be of very heavy construction.

According to the invention, in a press of the above-mentioned kind, the opposite lying bearing plates are connected with one another by means of tension members, particularly screw-threaded spindles taking up the pressing pressure and the conveyor bands or belts form between them from the inlet of the press to the first pair of rollers a wedge-shaped inlet space. The tension members in question relieve the roller frame from the pressing pressure so that it has only to take the weight of the machine parts so that it can be of considerably lighter construction. Moreover, resilient deformations under the influence of the high pressing pressures are effectively suppressed, this being absolutely necessary if high pressing pressures are to be obtained.

In the construction of the present invention the supports for the rollers and the cross elements, which are usually provided for in the presses of known type, are replaced by a number of bearing plates, these taking only the journals at the ends of the rollers and being of a relatively light construction.

A partial removal of the water or compression already occurs in the wedge-shaped inlet space formed according to the invention by the conveyor bands or belts so that the material for pressing enters the actual pressing part with a reduced volume and the pressing pressure between the rollers in the travel direction of the material can be rapidly and effectively increased. An inlet space

of this kind has also the advantage that when the rollers are adjusted the band parts limiting the inlet space are also automatically adjusted at the same time. The inlet space is therefore narrowed when the distance between the two bands is reduced and is correspondingly enlarged when this distance is increased.

One embodiment of the invention is illustrated in the accompanying drawing.

Fig. 1 is a vertical longitudinal sectional view of a press 10 embodying the invention.

Fig. 2 is a cross-section on the line II—II of Fig. 1.

Fig. 3 represents a half of a diagrammatical cross-section on the line III—III of Fig. 1.

Fig. 4 shows a similar section through a slightly modified form of construction.

The material to be pressed is advanced between two endless conveyor bands or belts 1, 2 in the direction of the arrow in Fig. 1. These conveyor bands or belts consist of flexible sheet metal plates or the like. The upper band 1 runs over the guide rollers 3, 4, 5 and a tensioning roller 6 while the lower band 2 runs over the guide rollers 7, 8, 9 and a tensioning roller 10. Fig. 1 shows roller groups A, B, C, D and E, each group being provided with four pairs of rollers 11, and an end group F. 15 The drawing is shown as broken between the groups D and E and any number of further groups of rollers may be provided between these groups.

A horizontal beam 13 is fixed at both sides of the press on a frame 12, adjusting spindles 14 being mounted rotatably but not displaceably in this beam at suitable distances apart. These spindles are provided at the top and bottom with right and left-hand threads engaging with which are nut members 15 rotatably mounted by means of journals 22 in the bearing plates 16. Each two pressing 20 rollers 11 bear on an intermediate roller 17 and with the exception of group A in the region of which the pressure is comparatively moderate, each two intermediate rollers 17 bear against a middle roller 18 which transmits the pressing pressure to the corresponding bearing plate 16.

Each of the bearing plates 16 is adjusted by actuating hand wheels 19 mounted on the spindles 14 enabling the associated group of rollers to be displaced parallel to itself or to be inclined differently in the direction of travel of the material to be pressed. As shown in Fig. 2, each 40 two spindles 14 lying opposite one another are coupled so that they have a common motion by means of sprockets 20 and a chain 21, this ensuring that the position of the rollers is always horizontal.

While the rollers 11 within a group lie in the groups 50 A—D in a plane it will be seen in group E these rollers are arranged along a curved envelope, facilitating the entry of the material to be pressed.

A wedge-shaped inlet space 23 is provided in front of the actual pressing part consisting of the groups A—F, 55 this space being bounded laterally by stationary, vertical side walls 24 and at the top and bottom by the bands or belts 1, 2 extending between the rollers 4 and 5 and 8 and 9. On the inside of the side walls 24 extend parallel to the bands 1, 2 angled strips 25 in which are inserted resilient packing strips 26, made for example of porous rubber, these strips bearing with a sealing action against the bands 1, 2.

In order to reduce the friction between the conveyor bands 1, 2 and these strips 26, thin sheet metal strips 65 can be inserted between. Instead of strips 26 made of porous rubber or the like, as shown in Fig. 3, sheet steel plates 28 stacked on top of one another can be used as shown in Fig. 4, the elasticity of which is retained and which are held in place by their being cambered 70 slightly in a transverse direction.

It may be of advantage if the sealing strips 26 or 28 are extended as shown in Fig. 1 into the actual pressing

part, for example, to the point 29 so that they also produce here a lateral edge sealing between the bands 1 and 2. In this case, it is an advantage if these strips gradually decrease in the direction of travel of the material to be pressed both in height and width. An edge sealing is generally no longer necessary for the portion of the press adjoining point 29 as the material is already well compressed at this point.

It can be seen that the material to be pressed is already compressed or has the water removed from it in the inlet space 23, at least in part. Linings are formed at this point on both the conveyor bands 1, 2, these being squeezed together to form a homogeneous layer on entering the pressing part. As shown in Fig. 1 two partitions 30, 31 provided in the inlet space 23 these enabling a material of other composition to be introduced between them, enabling webs of material to be obtained having two cover layers and a different kind of center layer. If only one partition is used, this enables two-layer webs to be produced.

High degrees of compression can be obtained in a single operation with the press according to the invention.

What I claim is:

1. A press for building up continuous webs of highly pressed material of low moisture content from small loose particles, which comprises, in combination, a frame, a pair of endless flexible metallic perforated conveyor bands forming vertically spaced-apart opposed runs, a plurality of guide rollers mounted in said frame and carrying said bands, the opposed vertically spaced-apart runs of said bands being adapted to move in the same direction, said opposed runs of said bands defining a pressing chamber in which the material being treated is continuously engaged by said bands and pressed while progressing with said bands, a plurality of pressing rollers engaged by and driven by the said conveyor bands exteriorly of said pressing chamber, said pressing rollers having a smaller diameter than said guide rollers and being disposed to bear against the portions of said bands between said guide rollers, said guide rollers directly acting upon said opposed runs of the conveyor bands and urging both of said runs in the direction of the medial plane of said pressing chamber, supporting rollers supporting and bearing against said pressing rolls in the direction of the medial plane of said pressing chamber, said pressing rollers and said supporting rollers being arranged in a plurality of independent groups arranged in spaced-apart series along said runs, each group consisting of two units arranged at vertically opposite sides of said pressing chamber and said runs, each unit comprising at least two pressing rollers and one associated supporting roller, and two laterally spaced-apart bearing plates carrying the ends of said pressing rollers and the ends of said supporting rollers of each unit and thereby combining said pressing rollers and the corresponding supporting rollers in each unit, tensioning means acting solely on said bearing plates of each group for tensioning the opposite units of a group towards each other, said tensioning means including means for effecting equal displacement of each of said opposite units of each group towards said pressing chamber, each of said groups being adjustable entirely independently of each other by said tensioning means.

2. A press as defined in claim 1, wherein said tensioning means are formed from screw spindles, each spindle having right-hand and left-hand threads, said screw spindles being guided in said frame to prevent axial movement, the plates of one unit of each group having nut means engaging the right hand threads, and the plates of the other unit of each group having separate nut means engaging the left hand threads so that by turning said screw spindles, equal movement of the opposite units of a group towards said pressing chamber is effected.

3. A press as defined in claim 1, wherein at least one of said endless conveyor bands has a portion ahead of said guide rollers disposed in front of the said groups inclined to form one wall portion of a wedge-shaped entrance chamber, stationary lateral walls defining additional wall portions of said wedge-shaped entrance chamber, and resilient sealing strips extending along said conveyor bands and secured to the said stationary walls, said strips bearing with a sealing action against the edges of said conveyor bands.

4. A press as defined in claim 3, wherein said sealing strips consist of sheet lamellae stacked on top of one another.

5. A press as defined in claim 3, wherein said sealing strips consist of sheet lamellae stacked on top of one another, said lamellae being cambered in a transverse direction.

6. A press as defined in claim 3, wherein said sealing strips consist of rubber, and strips of metal sheet are inserted between said first-named strips and said edges of the conveyor bands to reduce friction.

7. A press as defined in claim 1, wherein at least one of said endless conveyor bands has a portion ahead of said guide rollers disposed in front of said groups inclined to form one wall portion of a wedge-shaped entrance chamber, stationary lateral walls defining additional wall portions of said wedge-shaped entrance chamber, and resilient sealing strips extending along said conveyor bands and secured to said stationary walls, said strips extending along said runs and confining said pressure chamber, the height of said strips decreasing in the moving direction of said runs, and said strips bearing with a sealing action against the edges of said conveyor bands.

8. A press as defined in claim 7, further comprising at least one stationary partition inserted in said wedge-shaped entrance chamber and angularly subdividing said wedge-shaped entrance chamber to permit the production of webs of material consisting of several layers.
